UNITED STATES PATENT OFFICE.

VANDIVER J. VAN HORN, OF CHICAGO, ILLINOIS, ASSIGNEE TO UNION SPECIAL MACHINE COMPANY, OF CHICAGO, ILLINOIS, A CORPORATION OF ILLINOIS.

SEAM FOR SEWED ARTICLES.

1,100,508.

Specification of Letters Patent. Patented June 16, 1914.

Application filed February 13, 1911. Serial No. 608,371.

To all whom it may concern:

Be it known that I, VANDIVER J. VAN HORN, a citizen of the United States, residing at Chicago, in the county of Cook, 5 State of Illinois, have invented certain new and useful Improvements in Seams for Sewed Articles, of which the following is a description, reference being had to the accompanying drawing and to the letters and 10 figures of reference marked thereon.

My invention relates to new and useful improvements in seams for sewed articles, and has for its object to provide an ornamental seam for fabrics.

15 The invention consists in the matters hereinafter described and referred to in the appended claims.

The invention is illustrated in the accompanying drawings, in which,—Figure 1 is a 20 plan of a seam embodying my invention; Fig. 2 is a view on an enlarged scale showing the stitch formation; and Fig. 3 is a view similar to Fig. 2, illustrating a modification.

In the present illustrated embodiment of 25 the invention, there are two lines 1 and 2 of substantially parallel stitching. These are preferably but not necessarily, of the lock chain stitch type. A cross thread 3 passes back and forth diagonally between 30 the lines of stitching, being formed with circular loops 4, which embrace alternate needle punctures in each line of stitching. Another cross thread 5 is laid back and forth across the line of seam, the loops of 35 which also pass around alternate needle punctures in each line of stitching, the bights of the loops lying within the loops 4. As shown in Fig. 3, additional threads 6 and 7 are respectively woven in and out 40 of each line of stitching 1 and 2, passing back and forth across each line and secured by the threads between the needle punctures.

Having thus described my invention, what I claim as new and desire to secure by Letters Patent, is:—

45

1. A seam for sewed articles including a fabric, parallel lines of stitching, a cross thread having circular loops embracing alternate needle punctures in each line of stitching, and another cross thread having 50 loops thrown out from one side to the other of the line of seam, and also inclosing alternate needle punctures in each line of stitching.

2. A seam for sewed articles including a 55 fabric, parallel lines of stitching, a cross thread having circular loops embracing alternate needle punctures in each line of stitching, and another cross thread having loops thrown out from one side to the other 60 of the line of seam, and also inclosing alternate needle punctures in each line of stitching, the thread forming the bight of said loops lying within the circular loops 65 of the first cross thread.

3. A seam for sewed articles including a fabric, parallel lines of stitching, a cross thread having circular loops embracing alternate needle punctures in each line of stitching, and another cross thread having 70 loops thrown out from one side to the other of the line of seam, and also inclosing alternate needle punctures in each line of stitching, and a third thread extending along each of the parallel lines of stitching and interwoven with the needle punctures thereof. 75

In testimony whereof I affix my signature, in presence of two witnesses.

VANDIVER J. VAN HORN.
